CASING AND NOZZLE CONSTRUCTION
FOR ROCKET MOTORSCarolus L. Eksergian, Detroit, Mich., assignor, by
mesne assignments, to United States of
America

Application December 27, 1943, Serial No. 515,836

5 Claims. (Cl. 60—35.6)

1

This invention relates to rocket-propelled devices, particularly to rocket devices of the multi-jet type.

The primary object of the present invention is to provide a rocket-propelled device with a casing and jet arrangement which is of simplified and economical construction and which, for the most part is formed from a minimum number of parts, particularly parts which can be formed by simple machine turning operations.

Another object is to provide a rocket arrangement, the component parts of which are capable of being quickly and easily assembled, and which is particularly adaptable for rapid production in large quantities.

With the above and other objects in view which will be apparent from the following detailed description, to those skilled in the art to which the invention appertains, the present invention consists in certain features of construction and combinations of parts to be hereinafter described with reference to the accompanying drawing, and then claimed.

In the drawing which illustrates a suitable embodiment of the present invention;

Figure 1 is a side elevation of a rocket-propelled device in which the features of the present invention are incorporated; and

Figure 2 is an enlarged longitudinal section through the casing portion of the rocket-propelled device to which the present invention is directed.

Referring to the accompanying drawing, the rocket-propelled device embodies the device itself indicated in the outline by numeral 5, which may be in the form of an explosive projectile, a flare device, chemical device or any other device desired to be projected through space, and a trailing portion 6 secured to the device 5.

The trailing portion 6 to which the present invention is directed contains the propelling charge 7, shown in dotted outline, of suitable combustible material and includes a plurality of axially spaced propulsion jets.

According to the present invention, the trailing portion 6 is constructed of a plurality of tubular sections, including forward and rearward sections 8 and 9, respectively, and intermediate sections 10. The forward end of the forward section 8 is provided with internal threads 11 for threadably attaching to the device 5. Similarly, the rearward end of the rearward section 9 is provided with internal threads 12 for threadably receiving a stabilizing element 13. The sections 8, 9 and 10 are so arranged and formed that

2

adjacent ends of adjacent sections form between themselves an annular rearwardly-opening jet or Venturi passage 14 into which gases developed within the portion 6 by the burning of the propelling charge 7 flows through groups of circumferentially spaced apertures 15 provided in the sections 9 and 10 at axially spaced zones.

To this end, each of the sections 9 and 10 is externally threaded at its forward end and threaded into the adjacent forward section as indicated at 16. However, the sections may be otherwise secured together in circumferentially sealed engagement, such as for example, by welding or brazing. The discharge apertures 15 are provided in the forward ends of the sections 9 and 10 immediately adjacent the threaded connections 16. The rearward ends of the sections 8 and 10 are formed with skirt portions 17 extending rearwardly from the threaded connections 16, which skirt portions 17 surround in circumferentially spaced relation not only the apertured zones but also rearwardly adjacent zones 18 of the sections.

In order to provide the pressure developing jets or Venturi passages 14, the external faces 19 of the rearwardly adjacent zones 18 are formed to a conical contour, the taper being of least diameter adjacent the apertures 15, and those inner face portions 20 of the skirt portions 17 which surround the conical faces 19 are similarly contoured to conical shape but to a greater angularity so that the annular passages defined by the faces 19 and 20 will be of gradually increasing area in the rearward direction. In addition, the inner face portions 21 of the skirt portions 17 are continuously recessed to provide chambers surrounding the apertures 15 which are of greater external diameter than the entrance opening into the spaces between faces 19 and 20. There is thus provided between the overlapping but spaced rearward and forward ends of adjacent sections an annular Venturi passage 14 closed at its forward end and opening to the atmosphere at its rearward end in an axial direction, the walls of which passage are defined by the surfaces of such adjacent sections.

The gases resulting from the burning of the propelling charge 7 within the sections discharge through the apertures 15 into the surrounding enlarged chambers and thence under pressure through the passages between the faces 19 and 20.

While the number of tubular sections shown is such as to provide three axially spaced Venturi passages 14, it is obvious that, on the one hand,

additional intermediate sections 10 may be added to provide any desired number of passages, and on the other hand, the elimination of one intermediate section 10 will provide a two-jet device and the elimination of both intermediate sections will provide a single-jet device.

The stabilizing device 13 comprises a plug 22 threaded into the end of section 9, to which plug a plurality of rearwardly extending vanes 23 are secured, the vanes 23 being surrounded by a sheet metal band 24. Any suitable type of stabilizing vanes may be employed, however.

Various means of supporting the rocket or propelling charge 1 may be employed. The charge illustrated in broken outline may, for example, be supported on a rod 25 having a head 26 at one end and being threaded at its other end into the plug 22.

It is thus seen that the trailing portion 6 constituting the rocket motor is of extremely simple construction and that the tubular sections may be formed from tube stock and machined by simple lathe or automatic machine turning operations. Such operations tend toward the provision of true concentricity and proper balance of the structure.

It is obvious that the operations of assembly are reduced to a veritable minimum, which is extremely advantageous from the standpoint of quantity production during wartimes when manpower is at a premium.

Obviously, various changes may be made in the detailed construction and arrangement of the parts shown and described without departing from the spirit and substance of the invention, the scope of which is defined by the appended claims.

What is claimed is:

1. A rocket motor for rocket-propelled devices, comprising axially aligned, forward and rearward tubular sections adapted to contain a combustible propelling charge, the forward end of the rearward section being secured within the rearward end of the forward section, said forward section having an annular skirt portion surrounding the rearward section in circumferentially spaced relation and extending rearwardly from the region of securement of the forward and rearward sections to provide a rearwardly opening chamber, at least one aperture through the wall of said rearward section opening directly into said chamber, the walls of said chamber being contoured to provide a propulsion jet.

2. A rocket motor for rocket-propelled devices, comprising axially aligned, forward and rearward tubular sections adapted to contain a combustible propelling charge, the forward end of the rearward section being secured within the rearward end of the forward section, said forward section having an annular skirt portion surrounding the rearward section in circumferentially spaced relation and extending rearwardly from the region of securement of the forward and rearward sections to provide a rearwardly opening annular chamber, the rearward section having at least one aperture through the wall thereof opening directly into said chamber, the adjacent spaced wall surfaces of said sections which are rearwardly adjacent the aperture being conical and of greater spacing rearwardly of the aperture than adjacent the aperture.

3. A multi-jet rocket motor for rocket-propelled devices, comprising a plurality of axially aligned tubular sections adapted to contain a combustible propelling charge, the ends of adjacent sections fitting one within the other and being secured together in circumferentially sealed engagement, the outer sections having integral annular skirt portions extending axially from the regions of securement with and surrounding the inner sections in circumferentially spaced relation to provide annular chambers axially open at one end, said chambers being axially spaced apart, said inner sections having apertures through the walls thereof opening into said chambers, and the spaced walls of the sections which define said chambers being circumferentially contoured to provide propulsion jets.

4. A tubular structure for rocket-propelled devices, comprising three or more tubular sections adapted to contain a combustible propelling charge, each section having forward and rearward ends and having its forward end threaded into the next forward section and each section having an integral annular skirt portion at its rearward end extending rearwardly beyond its threaded connection with the next adjacent rearward section in circumferential spaced relation with said last-named section to provide an annular rearwardly opening chamber, each section having circumferentially spaced apertures in its forward end opening into the surrounding chamber for the discharge of gases resulting from the burning of the propelling charge into said chamber, the spaced walls of each said chamber being contoured to define a propulsion jet.

5. In a tubular structure for rocket-propelled devices and adapted to contain a combustible propelling charge, a pair of axially aligned tubular sections, one being threadably connected within the other, said other having an integral annular skirt portion extending axially beyond the threaded connection in surrounding circumferentially spaced relation with said one section to define an annular chamber open at one end, said one section having a plurality of circumferentially spaced apertures through the wall thereof, opening into said chamber, and the spaced walls of the sections rearwardly of said chamber being of conical shape to provide with said chamber a Venturi passage for the gases resulting from the burning of the propelling charge entering said chamber through said apertures.
